UNITED STATES PATENT OFFICE.

FREDERICK GRETSCH, OF BROOKLYN, NEW YORK.

MUSICAL INSTRUMENT.

Application filed March 1, 1926. Serial No. 91,527.

This invention relates to a musical stringed instrument and has for an object to provide an improved construction capable of use with all plectrum head instruments.

Another object of the invention is to provide an improved construction for musical instruments of the general type known as ukelele banjos, banjos, mandolin banjos and tenor banjos, wherein the vibratile member or skin is supported at a distance from the head proper of the instrument.

A further object, more specifically, is to provide in a musical instrument, an improved head structure wherein there is presented a rim and bottom with means spaced from the ring for supporting a diaphragm so that the sound produced may pass from both sides of the diaphragm and be deflected by the ring and body in a desired direction.

20 In the accompanying drawing—

Figure 1 is a plan view of a ukelele banjo, disclosing a preferred embodiment of the invention.

Figure 2 is a sectional view through Figures 1 on line 2—2.

Figure 3 is an enlarged fragmentary top plan view of part of the head shown in Figure 1, certain parts being broken away for better illustrating the location of certain parts.

Figure 4 is a perspective view of one of the angle brackets used in the head.

Referring to the accompanying drawing by numerals, 1 indicates the usual or preferred neck structure to which one end of the various strings 2 are connected in any desired manner, said strings passing over a bridge 3 of usual construction and from thence through various notches 4 in ring 5 to a point where they may be secured. The strings may be secured to ring 5 in any desired manner, as for instance, by being supplied with knots which are not capable of being pulled through the openings 4. Associated with the neck 1 is a head structure which consists of an outer rim 6 preferably of wood, a bottom 7 of wood, ring 5 preferably of metal and the diaphragm or skin 9 and associated parts. It will be noted that the rim 6 is continuous throughout and also the bottom 7 is continuous throughout while the ring 5 is spaced from rim 6 but permits

the sound to readily pass from the interior of the head structure outwardly away from the bottom 7 which acts as a sounding board. 55

A plurality of substantially L-shaped brackets 10 are secured to the rim 6 by suitable screws 11, each of said brackets having a threaded opening 12 for receiving the respective screws 13. A diaphragm supporting ring 14 preferably of metal, normally rests against the outwardly extending portion of the various brackets 10 and is firmly held against the same through the action of the diaphragm or skin 9, clamping ring 5 and 65 screws 13. The diaphragm 9 is provided with any kind of a rolled or enlarged edge 15 which is engaged by the inner edge of the ring 5 and pressed toward the brackets 10, until the desired tension is secured. The ring 5 is provided with an upstanding flange 16 which acts as a reinforcing structure to the ring and also as means for smoothing and holding part of the skin against the periphery of the ring 14. 70

By this construction and arrangement of bracket, ring 5 and associated parts, the diaphragm or vibratile member is suspended so as to be substantially flush with the top edge of rim 6. By thus suspending these 80 parts, the tone is greatly improved and the diaphragm is more or less protected. It will be understood that the instrument is played in the usual manner and that the various strings 2 vibrate to produce the desired 85 sound which are assisted and augmented by the diaphragm 9 and associated parts. Preferably the bottom 7 is solid so that the sound can be directed in a general direction toward the audience or toward any desired location. 90 Preferably the space between the rim 5 and the ring 6 is small, though if desired, it could be made much larger without in any way departing from the spirit of the invention. 95

What I claim is:

A stringed musical instrument having a bridge, and comprising a rim, a back closing one end of said rim, a plurality of right angled brackets supported within said rim intermediate the ends thereof, with the free ends projecting inwardly, a diaphragm supporting ring supported on the free ends of said brackets and within said rim, a diaphragm extended over said diaphragm sup-

porting ring, a clamping ring spaced from the rim and surrounding said diaphragm supporting ring, means for securing said clamping ring to said brackets and over the 5 diaphragm supporting ring whereby said clamping ring secures said diaphragm in place, a neck connected to said rim, and vi-

bratile strings connected to said clamping ring but out of contact with said rim, and supported on said bridge and extending 10 across the diaphragm and along the neck, and means for securing one end of said strings to said neck.

FREDERICK GRETSCHE.
